W. E. HATHEWAY

BUCKLE

Filed August 21, 1924

INVENTOR.
William E. Hatheway
BY

Geo. D. Phillips, ATTORNEY.

UNITED STATES PATENT OFFICE.

WILLIAM E. HATHeway, OF BRIDGEPORT, CONNECTICUT.

BUCKLE.

Application filed August 21, 1924. Serial No. 733,278.

To all whom it may concern:

Be it known that I, WILLIAM E. HATHeway, a citizen of the United States, residing at Bridgeport, in the county of Fairfield and State of Connecticut, have invented certain new and useful Improvements in Buckles; and I do hereby declare the following to be a full, clear, and exact description of the invention, such as will enable others skilled in the art to which it appertains, to make and use the same.

My invention relates to buckles of the character adapted for suspenders and articles of like character, it being an improvement on my former application, Serial No. 676,218, wherein teeth were formed on the inner edge of the opening in the floor and at right angles thereto to engage the webbing when forced thereagainst by the floor clamping sections. This arrangement proved more or less of a hindrance and loss of time in assembling the webbing to the buckle, and especially so when the upturned ears of the buckle frame were set at a more or less obtuse angle to the floor of the frame. Even with the floor teeth removed, the obtuse angle of the ears will restrict the webbing opening more or less and thus prevent easy threading of the webbing.

My present invention consists in forming teeth on the inner edge of the clamping floor sections and deflecting the same to form claws to engage the webbing when the sections are closed. The sections are adapted to be temporarily elevated above the floor to form a stop for the end of the webbing when the ears are approximately at right angles to the floor, and deflected below the floor and for the same purpose, when the obtuse angle of the ears obstruct the free entrance of the webbing above the floor.

Referring to the accompanying drawings, wherein the same characters of reference indicate like parts throughout the several views:—

Figure 1 represents a detail plan view of the buckle frame, showing the ears inturned and set at an obtuse angle to the floor of the frame.

Figure 2 is a plan view of the assembled buckle showing the floor clamping sections deflected below the floor and the ears thrown back or at an obtuse angle thereto.

Figure 3 is a side elevation of Figure 2, and broken view of the webbing.

Figure 4 is a plan view of an assembled

buckle of the depressed floor section type closed and broken view of webbing—

Figure 5 is an enlarged sectional view on the line 5—5 of Figure 4. 60

Figure 6 is an enlarged side elevation of the buckle frame showing the floor clamping section elevated above the floor and the ears at right angles thereto—

Figure 7 is an enlarged sectional view of the frame and webbing and full view of the closed lever, showing the elevated type of floor clamping sections closed—

Figure 8 is an enlarged broken detail view of a part of the floor of the frame and bar showing one of the ears before its elevation, and 70

Figure 9 is an enlarged broken detail rear view of the floor of the frame and bar showing one of the ears elevated. 75

The buckle frame consists of a single piece of metal comprising the floor 1, ears 2 and bar 3. The initial blanking operation, Figure 1, pierces the openings 5, 6, 7 and 8. The remaining portion of the floor is broken away to form the clamping sections 9 and 10 having the teeth 11, 12, also pierced from the floor 1. The openings 5, 6, 7, and 8, and the clamping sections, when elevated above the floor or depressed below the same, leaves the elongated opening 13 merging into the V-shaped openings 14 from which openings the teeth of the clamping sections 9 and 10 were pierced. In Figure 2 and Figure 3, these clamping sections are shown depressed below the floor with their teeth 11, 12, elevated at right angles to said sections to form claws to engage and hold the webbing. 85

The lever 15 is of the usual one-piece type having the eyes 16 journaled on the bar 3. 90 The blade 15^a of the lever is provided with the usual teeth 17.

When the ears 2 are thrown back at an obtuse angle to the floor of the buckle frame, as shown in Figures 1, 2, and 3, the opening 5 will be correspondingly narrowed, which will more or less retard the free insertion of the webbing in proportion as this angle is increased or diminished. Where there is any such obstruction, I prefer to depress the clamping sections 9, 10, below the floor to form a stop for the end of the webbing 18, which webbing is also located below the floor. The sections 9, 10, are then closed as shown in Figures 4 and 5. With the end of the webbing thus anchored to the floor sections the remaining portion of the web-

bing will pass around under the sections and over the upper surface of the floor, see arrows, Figure 5, and under the grip of the blade 15^a of the lever 15. It may be noted, 5 that, while the webbing in this construction does not fully cover both sides of the floor, it provides for the free insertion of the same when the ears are unduly thrown back.

When the ears 2 are erect, as shown in 10 Figures 6 and 7, or are not thrown back so far as to obstruct free entrance of the webbing above the floor, the floor clamping sections are elevated above the floor, as shown. In this construction, the webbing 18 is first 15 passed over the floor 1 of the frame with its end abutting the base of the upturned clamping sections, as shown in Figure 6. The sections are then closed down onto the underlying end of the webbing, Figure 7, 20 and said webbing is then carried over a portion of the upper surface of the buckle frame and thence under the lever 15 and around the edge of the frame and returned, see arrows, to form the loop 19, thence over 25 the frame and under the grip of the lever 15. This manner of threading the webbing will fully cover the metal of the frame and form what is known as a "rustless buckle."

It is customary to form the supporting 30 ears by turning up the edges of the frame to give them the necessary strength. This requires additional metal which adds materially to the cost of the buckle. To cheapen the construction and give the ears sufficient 35 support, I allow only sufficient metal for the ears and reinforce their base by the small fillet *a*, said fillet and base of the ears practically in line with the inner edge *b* of the floor. Elevating the ears above the floor of

the frame will also bring them at right 40 angles to their fillets, and impart a twisting effect to their base and thus add additional strength thereto. I propose also to incline the sides *c* for the purpose of concealing the same within the webbing as well as means 45 for reducing the stock.

Having thus described my invention what I claim is:—

1. An integral webbing holding sheet metal buckle frame comprising a floor, upturned ears and a lever supporting bar in spaced relation with the floor to form a slot, said floor having elongated webbing clamping sections pierced therefrom, said sections adapted to be temporarily offset from the 50 floor to form a stop for the end of webbing, said sections having teeth formed on their inner edges and disposed therefrom toward the floor to form retaining claws for the 55 webbing.

2. A sheet metal buckle of the character described comprising a one piece frame having a floor, ears and a cross bar in spaced relation with the floor to form a slot, a lever journaled on the bar, said ears reenforced at their base and inturned at an angle to said floor, the base of the ears and reinforce practically on a line with the edge of the floor underlying the lever, said floor having elongated webbing clamping sections pierced 70 therefrom, said sections adapted to be offset from the floor to form a stop for the end of webbing, said sections having teeth formed on their inner edge and disposed therefrom toward the floor to form retaining claws 75 for the webbing.

In testimony whereof I affix my signature.
WILLIAM E. HATHEWAY.
